(57) **CLAIM**

The ornamental design for a display screen or portion thereof with graphical user interface as shown and described.

DESCRIPTION

FIG. 1 is a front view of a display screen or portion thereof with graphical user interface showing our new design; and, FIG. 2 is a front view of another embodiment of a display screen or portion thereof with graphical user interface. The peripheral dashed broken lines depict a display screen or portion thereof, and form no part of the claimed design. The interior broken lines depict portions of the graphical user interface which form no part of the claimed design.

1 Claim, 1 Drawing Sheet

FIG. 2

FIG. 1
